UNITED STATES PATENT OFFICE

2,480,324

FURNACE

Nat Gold, Newark, N. J., assignor to Nat Gold and
Jack Marcus, doing business as G. M. Manu-
facturing Company, New York, N. Y.

Application October 5, 1944, Serial No. 557,299

1 Claim. (Cl. 263—11)

1

This invention relates to new improvements in gas furnaces.

Broadly, it is an object of my invention to provide an efficient furnace which will utilize the maximum amount of heat and will give a more rapid and uniform melt.

More particularly, an object is to provide inside walls of the furnace to conform to the shape of the crucible so that the flame envelopes the crucible.

Another object is to provide a furnace cover or series of covers with comparatively narrow flues in order to draw the flame around the crucibles.

For a fuller understanding of the nature and objects of my invention, reference is had to the following details of description in connection with the accompanying drawings, in which:

Fig. 1 is a perspective view of my furnace.

Fig. 2 is a top or plan view with the covers removed.

Fig. 3 is an enlarged section taken through line 3—3 of Fig. 2.

Fig. 4 is a perspective view of another furnace for upright or vertical crucibles.

Fig. 5 is a top or plan view of the modified furnace shown in Fig. 4, with the covers removed.

Fig. 6 is an enlarged sectional view taken through line 6—6 of Fig. 5.

Referring to the drawings, Figs. 1 to 3, inclusive, numeral 10 represents one form of furnace of rectangular shape comprising side walls 11 and end walls 12 which terminate in a base 13 to house a gas pipe 14 running through the length of the furnace. The walls 11 and 12 and the base 13 is preferably made of suitable refractory material. The inside walls 15 of the furnace are shaped to conform substantially to the shape of the crucible used. In the type shown in Figs. 1 to 3, the crucibles 16 are of circular cross section so that the inside walls are circular leaving sufficient space between the crucibles 16 and the inside walls 15 to permit the flames to envelope the crucible.

Along the top of the furnace 10 there is a long opening 17 through which the crucibles 16 are placed. The base 13 has a long channel 18, the top edges 19 of which have projecting shoulders 20 upon which the crucibles 16 rest. The space between shoulder 20 permits the flame to pass around the crucibles.

The long opening 17 is covered with a number of covers 21 which have extensions 22 which rest upon the top 23 of the furnace. The base portion 24 of the covers 21 fit within the opening 17. Each cover 21 has a narrow central opening or flue

2

25 which draws the flame around the crucible so that the entire crucible is enveloped in flame. Covers 21 are spaced so that the openings 25 are over the crucibles 16. An opening 26 is provided in each cover to facilitate the removal of the cover when desired. The insertion of a stick (not shown) into opening 26 will serve as a handle to remove the cover 21.

In using the furnace the valve 27 is opened 10 and the gas which passes through openings 28 in pipe 14 is lit. The crucibles 16 containing metal for melting is placed within the long opening 17 upon the projecting shoulders 20. The covers 21 are then placed over the opening 17, as 15 shown in Figs. 1 and 3. The flame will pass between the shoulders 20 and around the crucibles 16 since the inside walls 15 are shaped to conform to the shape of the crucible and deflect the flame towards and around the crucibles. The narrow openings 25 in covers 21 create 20 a draft and draw the flame around the top of the crucible so that practically no heat is lost. The covers 21 may be removed as above stated and the crucibles removed from the furnace when 25 the melt is complete.

The furnace walls may be covered with wood, metal or other desirable material. Such covering of the furnace wall may terminate with legs, as shown in Fig. 1.

The furnace 30 shown in Figs. 4, 5 and 6 functions in the same manner as furnace 10, described above, except that it is adapted for vertical crucibles 31 which are set upon pegs 32 so that the flame can pass beneath and around crucibles 31. The inside walls 33 of furnace 30 are of round 35 shape to conform to the shape of crucibles 31, as best shown in Fig. 5. The base 34 has an opening 35 for gas pipe 36 and also to provide air for the flame.

It is understood that changes may be made in the details of construction, that is, the inside shape of the walls of the furnace would be shaped to conform to the different shapes of crucibles, and the shape and size of the furnace would be made to house any desired number and size of crucibles, also different housings may be used to cover the refractory material of the furnace.

I claim:

50 A gas furnace of the character described comprising a housing of refractory material for crucibles, said housing having an opening at the top, a base, a gas pipe in said base, the inside walls of said housing shaped to conform to the shape 55 of said crucibles leaving sufficient space between

the inside walls of the housing and said crucibles to permit flame to envelope said crucibles, seats for said crucibles within said housing, said seats having projecting shoulders upon which said crucibles rest, permitting the flame to pass around said crucibles, covers for said top opening, said covers having narrow openings in vertical alignment with said gas pipe whereby the flame from said pipe is drawn around said crucibles.

NAT GOLD.
